DESIGN FOR A BUILDING FACADE OR SIMILAR ARTICLE

James Gosling, Jr., New York, N. Y., assignor to
Franklin Simon & Co., Inc., New York, N. Y., a
corporation of New York

Application August 7, 1942, Serial No. 107,844

Term of patent 7 years

To all whom it may concern:

Be it known that I, James Gosling, Jr., a citizen of the United States of America, residing at New York, in the county of New York and State of New York, have invented a new, original, and ornamental Design for a Building Facade or Similar Article, of which the following is a specification, reference being had to the accompanying drawings, constituting a part thereof.

Figure 1 is a front elevational view of a building facade, showing my new design.

Figure 2 is an end elevational view as seen from the left of Figure 1.

Figure 3 is a view of the right hand end of Figure 1.

I claim:

The ornamental design for a building facade or similar article, as shown.

JAMES GOSLING, JR.
